(57) **CLAIM**

The ornamental design for a chopstick, as shown and described.

DESCRIPTION

FIG. 1 is a first perspective view of a chopstick, showing my new design;

FIG. 2 is second perspective view of the chopstick;

FIG. 3 is a first side view of the chopstick;

FIG. 4 is a second side view of the chopstick;

FIG. 5 is a third side view of the chopstick;

FIG. 6 is a fourth side view of the chopstick;

FIG. 7 is a bottom view of the chopstick; and,

FIG. 8 is a top view of the chopstick.

The broken lines illustrate portions of the chopstick and form no part of the claimed design.

1 Claim, 4 Drawing Sheets
